UNITED STATES PATENT OFFICE.

OSCAR SCHORN, OF CLEVELAND, OHIO, ASSIGNOR OF ONE-HALF TO JOHN P. WEIGEL,
OF CLEVELAND, OHIO.

PAINTER'S TOOL.

1,110,351.

Specification of Letters Patent. Patented Sept. 15, 1914.

Application filed March 7, 1912. Serial No. 682,327.

To all whom it may concern:

Be it known that I, OSCAR SCHORN, a citizen of the United States, residing at Cleveland, in the county of Cuyahoga and 5 State of Ohio, have invented a certain new and useful Improvement in Painter's Tool, of which the following is a full, clear, and exact description, reference being had to the accompanying drawings.

10 This invention relates to painter's tools and has particular reference to a tool whereby liquid can be collected from the underside of a horizontal surface without dropping upon the body or clothes of the work- 15 man, and is particularly devised for the purpose of removing calcimine from ceilings, or for the washing of ceilings.

It is a well known fact among painters that the removal of a coat of calcimine is 20 more expensive than the application of such a coat, and that the removal of the calcimine from the ceiling is more difficult than the removal of the same from the whole remainder of the room. The method of re- 25 moving the same is to spray or sprinkle it with water from time to time until it has become thoroughly softened; when it will possess the thickness of molasses and be susceptible of removal by scraping. At the 30 same time its viscid and sticking character (owing to the fact of its being composed largely of an inferior grade of glue) has heretofore rendered its removal from a ceiling an extremely unpleasant operation.

35 One of the objects of my invention is the provision of a tool which shall permit the rapid and cleanly removal of such a substance from a ceiling and to catch and impound the same so as to prevent it from 40 falling upon the workman; the provision of a device of this character which can be operated in either direction and which may be employed in close proximity to the corners and obstructions; the provision of a 45 device of this character in which the squilgee can be readily replaced when worn; the provision of a device which can be quickly emptied and conveniently cleansed; the provision of a device of simple and durable 50 construction which can be made and sold at a price which shall recommend it to painters.

Further objects of my invention will be- 55 come apparent in the course of the following description and claims.

Generally speaking, my invention may be

defined as consisting of the combinations of elements recited in the claims hereto annexed and illustrated in the drawings accompanying and forming a part hereof, wherein,

Figure 1 is a perspective view of my im- 60 proved painter's tool and Fig. 2 is a vertical cross sectional view taken immediately within one of the end plates thereof and showing the same in operative position with 65 respect to the surface upon which it is used.

Describing the parts by reference characters, the device comprises an elongated hollow head having upwardly converging sides 1—1 and vertical ends 2—2, the whole 70 being secured to the end of a suitable handle 3 which preferably makes a right angle therewith, as shown at Fig. 1, but is inclined laterally from the head, as illustrated in Fig. 2. The handle may, if desired, be 75 braced by hollow metallic shells 4 in a well known manner. This construction provides a reservoir which has an upwardly opening elongated mouth defined by parallel lips 5—5, and between these lips I secure a 80 squilgee 7 of rubber or other suitable mate- 85 rial, the body whereof is preferably received in a U-shaped stiffening clip 8. Part of the squilgee lies inside and part outside the plane of the lips 5—5, but its sides are 90 spaced from both of said lips. Obviously a great number of expedients can be adopted for securing the squilgee to the head, the preferred method consisting in the employ- 95 ment of a metallic block 10 secured between the lips 5—5 at a point somewhat removed from each of the ends 2, each of said blocks having a slot for the reception of the clip 8 and having a set screw 11 whereby the clip is held in place. This construction per- 100 mits the ready replacement of squilgees as they become worn, or the employment of squilgees of different stiffness for different purposes. The arrangement of the blocks 10 at a distance from the ends 2 permits the reservoir to be emptied of collected liquid without the same being caught behind ob- 105 structions, while the position of the squilgee partly within and partly without the mouth of the reservoir causes the liquid re- moved from the surface being cleansed to be conducted within the reservoir. Owing to the fact that the squilgee is spaced from each of the lips, the tool can be used in either direction. The squilgee is extended 110

the full length of the device so as to permit the operation of the same to the very corners of the surface.

Having thus described my invention, what I claim is:

1. In a device of the character described, the combination with a receptacle having upwardly extending uninterrupted sides terminating abruptly in spaced lips which define an upwardly opening elongated mouth, of a squilgee projecting partly within and partly without said mouth and extending substantially the length thereof, but occupying only a part of its width, the interior of said receptacle being devoid of projections or pockets and being spaced from said squilgee at all points.
- 10 2. In a device of the character set forth, the combination with a reservoir member having upwardly converging sides terminating abruptly in spaced lips which define an upwardly opening elongated mouth, and also having substantially vertical end pieces, of a squilgee projecting partly within and partly without said mouth and spaced from both lips thereof and also spaced from the bottom of the reservoir, said squilgee extending from one end of said reservoir to

the other, and a handle projecting from a part of said reservoir member removed from 30 said mouth.

3. In a device of the character described, in combination, an elongated reservoir member having upwardly converging substantially flat sides, and substantially vertical 35 ends, the upper edges of said sides terminating in lips which define an elongated upwardly opening mouth, metallic blocks mounted between said lips at points removed from said ends and having squilgee 40 receiving slots, a squilgee having a rigid portion secured in said slots and extending from end to end of said mouth, said rigid portion being partly within and partly without the plane of said mouth and spaced 45 from both of said lips, the outer portion of said squilgee being flexible, means for detachably securing said squilgee in said slots, and a handle secured to said reservoir member at a point removed from said mouth. 50

In testimony whereof, I hereunto affix my signature in the presence of two witnesses.

OSCAR SCHORN.
